UNITED STATES PATENT OFFICE.

FREDERIC G. PERKINS, OF EVERETT, MASSACHUSETTS, ASSIGNOR TO THE BANKEETTE COMPANY, OF BOSTON, MASSACHUSETTS, A CORPORATION OF MASSACHUSETTS.

COIN BANK.

Application filed October 1, 1925. Serial No. 59,769.

The invention relates to an improvement in coin banks or receptacles essentially of the pocket type and to that type also in which the coins are locked within the bank and 5 cannot be withdrawn until the bank has been unlocked.

Among the objects of the invention are to provide a bank of the above character the body of which is composed of a number of 10 thin metal plates combined and co-operating with one another in such manner as to inherently form a very strong and rigid but light body structure having various compartments in it; to provide a very simple but 15 effective lock-secured means permitting of the insertion of coins into the bank through the end thereof controlled by the lock-secured means and their retention within the bank until the unlocking and removal of the 20 lock-secured means; to provide an improved type of concealed lock; to provide an arrangement whereby certain parts of the bank may assist in the retention of an encased card or plate bearing printed matter visible 25 through slots in the face of the bank, and to provide, also, an arrangement whereby all coins within the bank are visible either from the face or back.

The invention can best be seen and understood by reference to the drawings in which 30 an embodiment is shown and in which—

Figure 1 is a front elevation.

Fig. 2 is a rear elevation.

Fig. 3 is a section on the line 3—3 of 35 Fig. 1.

Fig. 4 is a front elevation of the upper end of the face of the bank with the cap shown in section.

Fig. 5 is a top elevation of the back of the 40 bank with the cap shown in section.

Fig. 6 is a vertical cross section of the top 45 end of the bank shown in enlarged detail.

Fig. 7 is an elevation of certain inside 50 portions of the bank.

Fig. 8 is a plan of the cap applied to one 55 end of the body of the bank.

Fig. 9 is a plan of the open end of the 60 body of the bank with the cap and coin-retaining comb removed.

Fig. 10 is a plan of the comb, and 65

Fig. 11 is a plan showing in enlarged detail the manner of connecting the plates forming the body of the bank along their sides.

Referring to the drawings:—

1, 2, 3 and 4 represent respectively spaced 55 plates parallelly arranged and forming collectively the body of the bank. Each of these plates is preferably rectangular in form and of relatively thin metal.

The plate 1 is provided along its sides with flanges 5, 5 extending at substantially right angles to the plate and from the ends of these flanges project out-turned edgings 6, 6. Intermediate its flanges 5, 5, parallel therewith and substantially equidistant therefrom and from one another, the plate 1 is provided with raised ribs 7, 7 formed respectively by bends in the metal.

The plate 2 is provided along its sides with 70 flanges 8, 8 out-turned at substantially right angles to the plate and from the outer ends of these flanges project out-turned edgings 9, 9 respectively. The plate 2 is also provided at points intermediate its flanges 8, 8 75 with ribs 10, 10 parallel with the flanges and substantially equidistant therefrom and from one another.

The plate 3, made preferably slightly broader than the plates 1 and 2, is provided 80 along its sides with inwardly-turned edgings 11, 11 which lap back onto the plate.

The plate 4, made substantially equal to the width of the plate 3, is provided along 85 its sides with flanges 12, 12 extending at substantially right angles to the plate. These flanges are further bent in the assemblage of the plates as will presently be explained.

The plates are combined to form the body of the bank as follows: In the assemblage 90 of the plates the plate 1 lies superimposed upon the plate 2. The flanges 5, 5 of the plate 1 lap by the flanges 8, 8 of the plate 2 with the edgings 6, 6 and 9, 9 of the respective plates lying nested together. The 95 flanges 5, 5 of the plate 1 are longer than the flanges 8, 8 of the plate 2 and thus operate to space the plate 1 along the sides from the plate 2 and also operate, along the sides, to close the space between the two 100

plates. The ribs 7, 7 of the plate 1 have engagement with the plate 2 by extension into grooves 13, 13 formed in the plate 2 by the bending of the metal for forming the ribs 10 5 on this plate. In other words, the ribs 7, 7 on the plate 1 extend into the ribs 10, 10 on the plate 2 and thereby assist not only in combining and strengthening the two plates, but act also as space members between them.

10 With the plates 1 and 2 thus combined, with the flanges 5, 5 and ribs 7, 7 on plate 1 co-operating with plate 2 as aforesaid, there is thus formed by and between the two plates a number of elongated compartments 14 open 15 at their opposite ends and each of a cross section substantially equal to the diameter and thickness of a coin.

The plate 2 in the assembled plates lies superimposed upon the plate 3 with the flanges 8, 8 of plate 2 extending to close the space between these plates along the sides, and also functioning to assist in the spacing of the plates along the sides. The edgings 9, 9 of the plate 2 have bearing against 20 the outer side edge portions of the plate 3. The ribs 10, 10 of the plate 2 bear against 25 the plate 3.

With the plates 2 and 3 thus combined with the flanges 8, 8 and ribs 10, 10 on plate 30 2 co-operating with the plate 3 as aforesaid, there is thus formed by and between these plates a number of elongated compartments 15 open at their opposite ends and each of a cross section substantially equal to the 35 diameter and thickness of a coin.

The plate 3 in the assemblage lies superimposed upon the plate 4 with the inturned edgings 11 of the plate 3 bearing against the plate 4 along its outer side portions and 40 acting as space members between these plates.

With the plates 3 and 4 thus combined and spaced from one another by the edgings 11, there is formed by and between these 45 plates a compartment 16 open at its opposite ends and of a cross section suitable to receive a card as will hereinafter be more fully explained.

Thus assembled, all the plates are combined by the flanges 12, 12 on the plate 4 which extend by the outer side edges of the plate 3 and by the edgings 6 and 9 respectively on the plates 1 and 2 and thence are turned and crimped over the edgings 6 on the plate 1, when all the plates become snugly bound together to form the body of the bank.

In the combined plates thus assembled, the plate 1 forms the back of the bank and 60 assists in forming the compartments 14. The plate 2 assists in forming the respective compartments 14 and 15 and functions as a diaphragm between these compartments. The plate 3 assists in forming the 65 compartments 15 and 16 and also functions

as a back to the compartment 16, while the plate 4 forms the face of the bank and assists in forming the compartment 16 and in the retention of all the other plates.

All the compartments 14, 15 and 16 of the bank are permanently closed at the bottom end in any suitable manner. This closure is preferably effected by means of a cap 17 fitted over the bottom end of the bank and permanently secured thereto in 75 any suitable manner.

At the opposite or top end of the bank a detachable closure is provided, locked to the body of the bank, and one which will permit of the insertion of coins into any of the coin-holding compartments 14 and 15, but prevent their removal and also the removal of any card, that may be contained in the compartment 16, until the unlocking and removal from the body of the bank of the detachable top closure when the coins or card may be removed as occasion requires.

To this end there is provided a V-shaped comb 20 of which 21 represents the back of the comb and 22 the teeth thereof. This comb is inserted to rest and turn upon the top edge of the plate or diaphragm 2 between the respective sets of compartments with the teeth 22 extending into the respective compartments. To permit of the mounting of the comb upon the plate 2 or diaphragm, the ribs 7, 7 and 10, 10 on the plates 1 and 2 are slightly cut away at their upper ends. When thus positioned and held in place, the turning of the comb upon the end of its supporting plate or diaphragm will permit of the insertion of coins into any of the compartments, but will prevent removal of the coins until the comb has been 100 removed from the body of the bank. In order to enable the comb to have ample freedom of movement the top end of the plate 1 is provided with slots or cut-outs 23 into which the teeth may swing. The teeth of the comb are also preferably made of spring metal so as to enable a coin to be jammed by them when inserted into a compartment apart from the turning movement 105 permitted the comb as aforesaid.

The comb is held in place and also any card which may be within the compartment 16 by means of a cap 25 fitting over the top end of the body of the bank. The cap comprises a capping 26 having slots 27 in its separated from one another by crossbars 28. Depending from the capping 26 is a rim 29. When the cap is in place on the top end of the body of the bank, the capping 26 operates to hold the comb snugly in place. It 115 also operates to close the compartment 16 in the bank in which the card is contained, and through its slots 27 permits of coins being inserted to pass into the various coin compartments 14 and 15. The rim 29 of the 120 130

cap fits down and around the top end of the body of the bank covering the slots or cut-outs 23 at the top end of the plate 1.

The cap is locked onto the body of the bank as follows: The plate 4 or face plate is provided at its top end with a slot or cut-out 30. This slot lies concealed beneath the rim 29 of the cap when the cap is in place. Secured to the interior side of the back plate 4 beneath the slot 30 and extending upwardly to lie in alignment with and just inside this slot is a thin metal plate 31 having in it an opening 32 presenting a top edge 33. The rim 29 of the cap or that portion of the rim which fits over the slot 30 and locking plate 31, is provided on the inside with a lug 34 which, when the cap is pressed down over the top end of the bank, is adapted to depress the locking plate 31 until the lug slips up by the edge 33 of the locking plate and into the opening 32 beneath it, when the locking plate will snap back into its normal position and the edge 33 thereof will lock behind the lug on the rim, thereby securely holding the rim in place. The lock is a concealed lock and may be unlocked by inserting any suitable tool or instrument through one of the slots 27 in the capping 26 and depressing the locking plate 31 sufficiently to admit of the lug slipping outwardly by the edge 33 of the locking plate, when the cap may be withdrawn.

In a bank of the present type it is desirable that the coins within its various compartments be visible at all times, and for this purpose the back plate 1 is provided with openings 35 preferably corresponding in number with the number of coins that will fill all the compartments 14. Coins contained within any of the compartments 15 are also visible through aligned openings 36 in both the plates 3 and 4. These openings have a determinate location with relation to the location of the coins contained in the compartments 15 on account of slots 37 formed in the face plate 4 through which printed matter on a card 38 located in compartment 16 is visible. In this connection it will be explained that a card contained in compartment 16 is adapted to carry certain printed matter such as advertising matter, which will show through the slots 37 in the face plate. Accordingly the slots in the face plate and plate 3 require a certain determinate positioning of the openings 36 therein if all of the coins contained within the compartments 15 are to be visible, and this positioning is obtained by so locating the openings 36 in the face plate and the openings in alignment therewith in the plate 3, that the meeting rims of two coins and portions of the respective coins adjacent their rims are visible through each of the openings 36. In this way not only are all the

coins visible through the face plate, but allowance is also made for the display of the printed matter through the same plate. In this connection it will be understood that the card inserted in compartment 16 is provided with coin display openings like those formed in plates 3 and 4 and which openings in the card will be in alignment with the openings 36 in the plates 3 and 4 when the card is in place.

Having thus fully described my invention, I claim and desire to secure by Letters Patent of the United States:—

1. In a coin bank, the body of the bank comprising a number of spaced parallelly arranged plates forming a number of compartments between them, certain of said plates having flanges extending from the sides thereof with edgings outwardly displaced from said flanges and nested together, the flanges on the one of said plates being longer than the flanges on the next adjacent plate and lapping by the same, and a certain other of said plates having flanges along its opposite sides extending around and crimped onto said nested edgings for combining all of said plates.

2. In a coin bank, the body of the bank comprising a number of parallelly arranged plates forming by and between them coin-receiving compartments and a separate card-receiving compartment, the card-receiving compartment being formed adjacent an outer one of said plates, certain of said plates assisting in the formation of the coin-receiving compartments having edgings along either side thereof nested together and extending from turned flanges on the sides of said plates, the flanges on one of said plates being longer than the flanges on the next adjacent plate and lapping by the same, certain other of said plates assisting in the formation of said card-receiving compartment having edgings along either side thereof nesting with the edgings of said flanged plates, and flanges on the opposite sides of said outer plate extending around and crimped onto said nested edgings for combining all of said plates.

3. In a coin bank, the body of the bank comprising a number of spaced parallelly-disposed plates connected to one another and closed along their sides, certain of said plates having rib-forming bends therein extending to engage the next adjacent plate with bearing against it and dividing the space between the plates into separate compartments, certain of said ribs on the one of said plates extending to fit within sockets formed by the rib-forming bends in the next adjacent plate.

4. In a coin bank, the body of the bank comprising a number of spaced parallelly-arranged plates forming by and between them coin-receiving compartments and a separate card-receiving compartment ad-

- 15 jacent an outer one of said plates, a releasable cap fitting over said body and over the open ends of all of said compartments at one end of the bank, said cap having a depending rim lapping by and onto said body of the bank, and releasable means forming a concealed locking engagement between said rim and said outer plate to which the card-receiving compartment is adjacent. 70
- 19 5. In a coin bank, the body of the bank comprising a number of spaced parallelly-arranged plates forming by and between them coin-receiving compartments and a separate card-receiving compartment adjacent an outer one of said plates, a releasable cap fitting over said body and over the open ends of all of said compartments at one end of the bank, said cap having a depending rim lapping by and onto said body of the bank, a concealed resilient tongue having a locking edge carried by said outer plate and lying beneath said rim when the cap is in place, and a lock on said rim having releasable engagement with the locking edge 75 of said tongue when the cap is in place. 80
- 15 6. A coin bank comprising a body having a number of connected plates forming by and between them coin-receiving compartments, and a separate card-receiving compartments adjacent an outer one of said plates, a removable coin-retaining device arranged to permit of the admission of coins to said coin-receiving compartments but preventing the removal of coins therefrom until 85 the removal of said device, a releasable cap fitting over said device and over the open ends of all of said compartments at one end of the bank, said cap having a depending rim lapping by and onto said body of the bank, a releasable means forming a concealed locking engagement between said rim and said outer plate, and means for closing the open ends of all of said compartments at the opposite end of the bank. 90
- 40 7. A coin bank comprising a body having a number of spaced, parallelly arranged, connected plates forming by and between them coin-receiving compartments and a card-receiving compartment, said card-receiving compartment being formed adjacent an outer one of said plates, said outer plate having slots in it through which portions of a card contained in said card-receiving compartment are visible, a releasable cap controlling the entrance to all of said compartments at one end of the bank, said cap being provided with a depending rim lapping by and onto said body, a slotted resilient tongue having a locking edge carried by said outer plate and lying beneath said rim when the cap is in place, and a lug on said rim having releasable engagement with the locking edge of said tongue when the cap is in place. 95
- 45 8. A coin bank comprising a body having a number of spaced, parallelly-arranged plates, one a back plate, one a face plate and a number of interposed plates, means for connecting said respective plates whereby an outer coin-receiving compartment will be formed by and between the back plate and one of said interposed plates, an inner coin-receiving compartment will be formed by and between certain of said interposed plates, and a card-receiving compartment will be formed by and between one of said interposed plates and said face plate, said back plate having openings therein through which coins contained in said outer coin-receiving compartment are visible, said face plate having slots therein through which portions of a card containing in said card-receiving compartment are visible, said face plate and that one of said interposed plates co-operating with said face plate to form said card-receiving compartment having 100 therein aligned openings arranged out of alignment with the slots in said face plate whereby coins within said inner coin-receiving compartment are visible, means permitting of the admission of coins to said coin-receiving compartments but preventing their withdrawal, and a releasable lock-controlled means controlling the withdrawal of contained coins from said coin-receiving compartments and a contained card from said 105 card-receiving compartments. 110
- 40 9. A coin bank comprising a body having a number of connected plates forming by and between them coin-receiving compartments and a separate card-receiving compartment adjacent the outer one of said plates, a coin-retaining device arranged to permit of the admission of coins to said coin-receiving compartments but preventing the removal of coins therefrom until the removal 115 of said device, a releasable cap fitting over said device and over the open ends of all of said compartments at one end of the bank, said cap having slotted openings therein through which coins may be passed, said cap having also a depending rim lapping by and onto the body of the bank, a releasable means forming a concealed locking engagement between said rim and said outer plate and which means is releasable by entry through 120 one of the slots in said cap, and means for closing the open ends of all of said compartments at the opposite end of the bank. 125
- 45 10. A coin bank comprising a body having a number of connected plates forming by and between them coin-receiving compartments and a separate card-receiving compartment adjacent the outer one of said plates, a coin-retaining device arranged to permit of the admission of coins to said coin-receiving compartments but preventing the removal of coins therefrom until the removal of said device, a releasable cap fitting over said device and over the open ends of all of said compartments at one end of the bank, said 130

cap having slotted openings therein through which coins may be passed, said cap having also a depending rim lapping by and onto the body of the bank, a slotted resilient tongue having a locking-edge carried by said outer plate and lying beneath said rim when the cap is in place, a lug on said rim having releasable engagement with the locking edge

of said tongue when the cap is in place, said tongue being arranged whereby it may be bent and the lug released permitting withdrawal of the cap by entry through one of the openings in the cap, and means for closing all of said compartments at the opposite end of the bank.

FREDERIC G. PERKINS.
